KNOCKDOWN STOOL-EASEL

Francis C. Holbrook, Brooklyn, N. Y.

Application August 19, 1949, Serial No. 111,121

4 Claims. (Cl. 45—129)

1

This invention is a novel knockdown stool-easel, being an article of manufacture in the nature of a light, portable and collapsible combination constituting a knockdown structure which adapted for various uses such as sketching or painting by artists indoors or outdoors, or similar uses.

The general object of the present invention is to afford an inexpensively constructed article of manufacture, light in weight and readily carried from place to place; and more especially the main object is to supply such an article which can be knocked down readily and is then in such compact form as to be easily carried, handled, set up and knocked down. A further object is to afford such an article which is simple of structure and convenient in use, providing a comfortable seat or stool, in combination with a highly convenient easel adapted to support any conventional form of workboard, sketching pad, painting frame or the like, and to be adjusted at will. Another object is to provide such an article which, when set up, is readily latched or locked against collapse and yet is readily unlatched or released for the purpose of rearranging the parts into their compact or knockdown form.

Other and further objects and advantages of the invention will be explained in the hereinafter following description of an illustrative embodiment of the invention, or will be understood by those conversant with the subject. To the attainment of such objects and advantages the present invention consists in the novel knockdown stool-easel, and the novel features of combination, construction, arrangement and detail herein illustrated or described.

In the accompanying drawings, Fig. 1 is a top plan view of the stool-easel of this invention with the parts in their set-up position, showing the stool elements at the lefthand part of the drawing and the easel elements at the righthand part thereof, and with one practical position of the workboard shown in dotted lines.

Fig. 2 is a side elevation of the set-up article of Fig. 1, showing one of several possible positions of the workboard there indicated in full lines.

Fig. 3 is a top view of the article in its relatively flat knockdown condition or adjustment, which figure shows that when the stool seat is circular, this and its extension parts present a banjo-like form.

Fig. 4 is a side elevation of the parts in their knockdown position.

Fig. 5, partly in side elevation and partly in

section on the line 5—5 of Fig. 1, shows a detail in the relation of the seat and a leg thereof, with releasable latch means between the seat and the leg.

5. Fig. 6, looking from the side, is a section taken on the line 6—6 of Fig. 1 showing a detail as to the support and the clipping or clamping of the workboard upon the adjustable elements of the easel.

10. In the drawing the mechanical parts are first enumerated as follows. The workboard or artists' pad or frame 10 appears in Figs. 1 and 2. At the left or stool end of the article or stool-easel the seat 11 is shown of round form although it may be of other shape, and may be composed of wood or plastic material but preferably a light metal as aluminum alloy.

By means of hinges 12 each comprising a small bracket and a connecting pin, underneath 20 the seat 11, the two rear legs 13, 13 are mounted to swing between their set-up and knockdown positions; and while these legs are shown cylindrical they may be of flat form like the auxiliary leg or easel prop 20 to be described. To hold each leg in its set-up position a latch 14—15 is shown in Figs. 2, 4 and 5, consisting of a strip spring 14 cooperating with a projection 15. The spring 14 may be apertured to receive the latching projection 15 at the top of the leg; the latching parts 25 snapping into engagement when the article is set up. It is only necessary to press back the spring end to release the leg for folding in at the underside of the seat.

The means interconnecting the rear or stool parts and the easel parts at the front consists of the longitudinal axial beam or rigid extension bar 17, secured or bolted unitarily to the seat, as by the beam flanges 18.

Taking a midpoint of the beam 17 as being the 35 dividing point between the stool elements and the easel elements, the latter comprise the auxiliary leg or prop 20 together with the easel arm 22 and parts carried thereby. These parts 20 and 22 are 40 connected to the front part of the beam to swing pivotally between their working and knockdown positions, each of them about a transverse axis. Preferably a single axle or pivot bolt 23 serves for the swinging mounting of both the easel prop 20 and the easel arm 22; this bolt passing through the beam as the fixed element, and through the arm and the prop, the far end of the bolt being 45 threaded to receive a complementary member as the wingnut 24. This holding or gripping member 24 may be tightened in either the set-up or the knockdown position of the parts, this arm

angement providing sufficient friction to hold the swingable parts 20 and 22 in their respective adjusted or set positions.

To improve the friction and holding function of the parts 20 and 22, relatively to each other and to the beam 11, the washer under the wing-nut may be a friction washer, and may indeed be increased in size and area from what is shown. It being especially important that the easel arm 22 should hold its adjusted position, either set up or knocked down, this arm may be assembled between the beam and the prop, thus increasing further the holding surface and friction. When the artist is at work in the field the tilted adjustment of the workboard thereby will not be easily disturbed.

When the parts are knockdown, as in Figs. 3 and 4, the cross bar 26, at the free end of the easel arm 22 serves the additional purpose of overlying not only the infolded end of the prop 20 but also the infolded end of the legs 13, 13. The parts are then in their carrying position, and the tightening clamping of the wingnut secures them thus, without the need of a special lock or hook to prevent displacement of the four unfolded or knocked down parts.

As a means of supporting and holding, clipping or clamping a workboard 10 or the like upon the easel arm 22 said arm is shown as provided with a crossbar 26, near its free end, this being of substantial lateral dimension to accommodate the expected size of workboard. By means of a threaded bolt 27, engaging a threaded bore in a lug 29 at the end of the arm 22, an overlying clamping member or block 28 may be brought down into contact upon the far or outer edge of the workboard. By this device the workboard 10 is squeezed and firmly held. The small parts 27 and 28 may be detached and carried separately to render the collapsed article better transportable.

By these means the workboard rests fairly steadily upon the crossbar 26, whereat it is clamped, with a third contact or rest upon the top of the beam extension 17; while, for a shorter workboard a second crossbar 30 may be provided extending right and leftward from the easel arm 22. This supplemental member serves not only as a pad-support but also, as will be understood from Fig. 3, as a convenient cross-handle for carrying the collapsed stool-easel.

The mechanical parts of the stool-seat of this invention having been identified, the subject matter, being a combination of elements, may be explained further as to the structures, actions and cooperations of the parts. The stool seat 11 is normally supported by its pair of symmetrically spaced-apart depending rear stool-legs 13, which are mounted by the hinges 12 so that the legs may be swung from their working position of Figs. 1 and 2 in a somewhat converging manner to their collapsed positions of Figs. 3 and 4, where the legs lie flatly and non-parallel against the underside of the seat.

When each leg has been set up, the spring lock device 14, 15 holds the legs rigidly in position. The need of a third leg beneath the seat is dispensed with, since this function is provided by the easel prop or leg 20. The rear legs could be telescopic for reduction of knockdown dimensions, but the disclosed arrangement dispenses with this while affording sufficient set-up leg length for general purposes. The frontward position of the auxiliary leg operates to increase the area of the base of support comprised be-

tween the points where the three legs rest upon the ground or floor, affording ample stability.

In changing the adjustment of the parts between set-up and knockdown positions the beam 17 acts as a rigid part of the seat 11, and near the front part of the beam the swinging elements 20 and 22 are mounted to swing about the cross axis provided by the bolt or threaded axle 23 with which cooperates the tightener or wing-nut 24, readily operable by hand, for the readjusting and setting of the parts.

While seated on the stool seat the artist can readily adjust the easel arm to any desired up-slope, as will be clear from Fig. 2; this by loosening the wingnut, setting the easel arm and workboard, and tightening the wingnut, all without loss of stability by the loosening and tightening of the easel prop leg 20 simultaneously therewith.

There has thus been described a knockdown stool-easel embodying the principles and attaining the objects of the present invention; and since many matters of combination, construction, arrangement, design and detail may be variously modified without departing from such principles, it is not intended to limit the invention to such matters except to the extent set forth in the appended claims.

What is claimed is:

1. A portable, knockdown stool-easel comprising a stool-seat, leg means depending from the rear section of said stool-seat in set-up position and hinged to said stool-seat to permit said leg means to be folded against the underside of said stool seat in knockdown position, a beam rigidly secured to the underside of said stool-seat and projecting substantially forward therefrom, a pivot clamping bolt supported on the forward end of said beam, an easel prop pivotally supported on said bolt and movable about the axis of said bolt from depending set-up position to folded knockdown position along said beam and against the underside of said stool-seat, and an easel arm pivotally supported on said bolt and movable independently of said prop about the axis of said bolt from extended set-up position forward of said beam to folded knockdown position along said beam and against the underside of said stool-seat, said bolt including tightening and loosening means manipulable into position to loosen said bolt and to permit thereby the pivotal movements of said easel arm and said prop about the axis of said bolt relative to said beam and manipulable into tight clamping position to hold said prop and said easel arm selectively either in set-up position or in knockdown folded position.

2. A portable, knockdown stool-easel comprising a stool-seat, leg means depending from the rear section of said stool-seat in set-up position and hinged to said stool-seat to permit said leg means to be folded against the underside of said stool seat in knockdown position, a beam rigidly secured to the underside of said stool-seat and projecting substantially forward therefrom, an easel prop pivotally supported on the forward end of said beam for movement from depending set-up position to folded knockdown position along said beam and against the underside of said stool seat, an easel arm pivotally supported on the forward end of said beam for movement from extended set-up position forward of said beam to folded knockdown position along said beam and against the underside of said stool seat, a crossbar on the forward end

of said easel arm for supporting a workboard in set-up extended position of said easel arm, said easel arm being long enough, whereby in folded knockdown position of said easel arm, said crossbar overlies said leg means on the underside of said stool seat in folded knockdown position of said leg means, and releasable means for holding said easel arm in folded knockdown position and for holding thereby said leg means in folded knockdown position.

3. A portable, knockdown stool-easel comprising a stool seat, leg means depending from the rear section of said stool seat in set-up position and hinged to said stool seat to permit said leg means to be folded against the underside of said stool seat in knockdown position, a beam rigidly secured to the underside of said stool seat and projecting substantially frontward therefrom, an easel prop pivotally supported on the forward end of said beam for movement from depending set-up position to folded knockdown position along said beam and against the underside of said stool seat, a pivot clamping bolt supported on the forward end of said beam, an easel arm pivotally supported on said bolt and movable about the axis of said bolt from extended set-up position frontward of said beam to folded knockdown position along said beam and against the underside of said stool seat, a crossbar on the forward end of said easel arm for supporting a workboard in set-up extended position of said easel arm, said easel arm being long enough, whereby in folded knockdown position of said easel arm, said crossbar overlies said leg means on the underside of said stool seat in folded knockdown position of said leg means, said pivot bolt including tightening and loosening means manipulable to permit the pivotal movement of said easel arm about the axis of said bolt or to hold said easel arm selectively either in set-up position or in knockdown folded position.

4. A portable, knockdown stool-easel comprising a stool seat, a pair of spaced rear legs pivotally connected at one end to the underside of said stool seat and movable between set-up seat supporting position and collapsed knockdown position against the underside of said stool seat, a beam rigidly secured to the underside of said

stool seat and extending therealong in centered position with respect to said rear legs, the front section of said beam projecting forwardly from said stool seat, a pivot clamping bolt supported on the forward end of said beam and having a clamping wing-nut to tighten or loosen said bolt, an easel prop pivotally supported on said bolt and movable about the axis of said bolt from depending set-up position to folded knockdown position along said beam and against the underside of said stool seat, an easel arm pivotally supported on said bolt and movable independently of said prop about the axis of said bolt from extended set-up position frontward of said beam to folded knockdown position along said beam and against the underside of said stool seat, and a crossbar on the forward end of said easel arm for supporting a workboard in set-up extended position of said easel arm, said easel arm being long enough, whereby in folded knockdown position of said easel arm, said crossbar overlies said rear legs on the underside of said stool seat in folded knockdown position of said rear legs, said bolt being adapted to be loosened by manipulation of said wing-nut to permit the pivotal movements of said easel arm and said prop about the axis of said bolt relative to said beam and being adapted to be tightened by manipulation of said wing-nut to hold said prop and said easel arm selectively either in set-up position or in knockdown folded position and to hold said rear legs in folded knockdown position by the confining action of the overlying crossbar.

FRANCIS C. HOLBROOK.
